UNITED STATES PATENT OFFICE.

CYRIL G. PARKS, OF MINNEAPOLIS, MINNESOTA.

PACKAGE-CLASP.

1,038,785.

Specification of Letters Patent. Patented Sept. 17, 1912.

Application filed April 17, 1911. Serial No. 621,640.

To all whom it may concern:

Be it known that I, CYRIL G. PARKS, of Minneapolis, Hennepin county, Minnesota, have invented certain new and useful Improvements in Package-Clasps, of which the following is a specification.

The object of my invention is to provide a device for clasping papers for filing purposes, or packages of letters or other documents to prevent them from becoming separated or scattered, the clasp being readily applied and applicable to various sizes of packages, and easily tightened on the package or entirely removed from the package.

The invention consists generally in a clip, preferably metallic, a tape attached at one end to said clip and passed around the package, said clip having means to engage the free end of the tape for temporarily securing it.

In the accompanying drawings forming part of this specification, Figure 1 is a perspective view of a package with my invention applied thereto, Fig. 2 is a detail view of the clip separated from the tape, Fig. 3 is a similar view, showing the preferred means for attaching the tape to the clip.

In the drawing, 2 represents a package around which the tape is placed and 3 is a clip, preferably of thin sheet metal, having laterally projecting arms 4 and 5 parallel, substantially, with one another and located on the same side of the clip with a space between them. The arm 4 has a series 35 of prongs 6 on one edge that are adapted to engage one end of the tape 7 and, passing through the tape, are bent backwardly toward the arm to secure the tape to the clip. The arm 5 is preferably provided with similar prongs on each side, as shown in Fig. 2, the outer series of prongs engaging a tab 8 of tape or other suitable material and securing it to the clip. The free end of the tape is passed around the package through the 45 opening between the arms and the operator, grasping the free end of the tape with one hand and the tab 8 with the other hand, can easily draw or tighten the tape around the package until the desired degree of compression is obtained. The inner prongs on the arm 5 are then thrust through the tape, as

illustrated in Fig. 1, and the expansion of the papers in the package will tighten the tape sufficiently to hold it against accidental displacement on the package and hold the 55 papers securely bound together until such time as it is desired to open the package. At that time the operator will grasp the tab with one hand and pulling on the free end of the tape with the other hand may disengage the tape from the inner prongs of the arm 5 and release the clasp and free the papers. The arms 4 and 5 are preferably in the same plane with the part 3 connecting them, and the clip will lie flat on the package 60 and allow it to be handled or filed without catching on other papers or on the sides of the pigeon-hole in which the package may be thrust. The clip lying flat on the package 65 will also allow one package to be placed 70 upon another in compact form.

I do not wish to be confined to the precise form of clip shown herein, as it may be modified in various ways and still be within the scope of my invention as defined by the 75 appended claims.

I claim as my invention:

1. A package clasp comprising a clip, U-shaped substantially in form, one of the arms of said clip having prongs on its outer 80 edge, a tape having one end attached to said prongs, the other arm having prongs or points on both of its edges, a tab attached to the outer prongs of said other arm, the free end of said tape adapted to enter the space 85 between said arms and engage the inner prongs of said other arm.

2. A package clasp comprising a clip, U-shaped, substantially, in form, a tape having one end attached to one of the arms of said clip, a tab attached to the outer edge of said other arm, the free end of said tape adapted 90 to enter the space between said arms and said other arm having means on its inner edge to engage the free end of said tape, substantially as described.

In witness whereof, I have hereunto set my hand this 7th day of April 1911.

CYRIL G. PARKS.
